GLOW-TUBE VOLTAGE INDICATOR

William C. Linton, Washington, D. C.

Application August 13, 1948, Serial No. 44,049

3 Claims. (Cl. 171—95)

1

The present invention relates to voltage indicators of the lamp type for low potential commercial circuits wherein a visible indication is obtainable as to the approximate relative potential of an electrical conductor to ground or another conductor and also as to whether alternating or direct current is passing through the conductor.

An object of the present invention is to provide a rugged and compact instrument capable of housing a voltage indicator of the above type and yet be comparatively inexpensive in the cost of manufacture to render the same commercially desirable.

Other objects will be in part obvious and in part pointed out hereinafter as the description continues.

In the accompanying drawings:

Fig. 1 is a side elevation of the instrument embodying the present invention.

Fig. 2 is a vertical sectional view of the same.

Fig. 3, a horizontal section taken on the line 3—3 of Fig. 1 in the direction of the arrow points.

Fig. 4 is a similar view taken on the line 4—4 of Fig. 1 in the direction of the arrow points.

Fig. 5 is a similar view taken on the line 5—5 of Fig. 1 in the direction of the arrow points.

Fig. 6 is another horizontal section taken on the line 6—6 of Fig. 2 in the direction of the arrow points.

Fig. 7 is a similar view taken on the line 7—7 of Fig. 2 in the direction of the arrow points.

Fig. 8 is a plan view of the core, and

Fig. 9 is a plan view of the fabricated lamp type voltage indicated prior to being inserted within the core of the instrument.

The instrument herein comprises a casing 1 formed of a cylindrical tube of heavy fibre with its opposite ends opened and in the wall of this tube is punched a row of three openings 2. A name plate 3 preferably made from plastic materials partly encircling the outer wall of the tube and is attached thereto by means of the drive screws 4. This name plate has formed therein a row of three openings which register with the openings 2 of the casing 1 and adjacent the uppermost openings the name plate has thereon 110—125, adjacent the intermediate openings 220—240 and the lowermost openings 440—600.

A core 5 in the form of a cylindrical rod of plastic materials and of the same length as that of the tube 1 has an exterior diameter the same as that of the interior diameter of the tube whereby when the core is inserted within the tube, in the manner as best shown in Fig. 2 of the draw-

ings, a wedged fit will be effected therebetween. One end of this core 5 has formed therein a longitudinally extending recess 6 and in the outer end of the latter is driven a milled contact holder 7 through which extends a contact pin 8. A tightening screw cap 9 is connected to the holder 7 in order to grip the pin 8 for retaining the latter in various extended positions from the core. The opposite or lower end of the core has a L-shaped slot 10 formed therein through which extends a flexible wire coated conductor 11. One end of this conductor is knotted as at 12 and when the latter is seated within the enlarged horizontal section of the L-shaped slot the conductor will be prevented from being drawn from the vertical section of the slot. This forms a connection between the core and conductor without any separable fastening elements. This wire conductor 11 may be of any desired length but its opposite end extends within the tube shaped handle 12. This handle 12 is cut from a single cylindrical tube of plastic material having its opposite ends opened and within the opened end opposite to that through which the conductor 11 extends is a contact holder 13. This contact holder 13 is of the same construction and design as that of the contact holder 7 and has adjustably extending therethrough another contact pin 14. A soldered connection 15 is effected between the contact holder 13 and the conductor 11.

The visible indicator as employed in this instrument is of a network construction, as is best shown in Fig. 9 of the drawings and consists of three miniature neon glow lamps A, B and C. Each lamp comprises a glass bulb having sealed therein two spaced electrodes 16 and from each electrode extends the lead wires 17 and 18. The lead wire 17 of the lamp A is electrically connected as at 19 to a lead wire 20 and the lead wire 18 thereof has included therein a conventional carbon stick resistor 21 of the value of 150,000 ohms and is connected as at 22 to a lead wire 23. The lead wire 18 of the lamp B is connected in series with a resistor 24 of the value of 100,000 ohms to the wire 20 as at 19 and the other lead wire 17 is connected as at 25 to a conductor 26. This conductor 26 has arranged in series therewith and the connection 22 of the conductor 23 two resistors, one indicated as at 27 being of the value of 150,000 ohms and the other 28 of the value of 50,000 ohms. A resistor 29 of the value of 100,000 ohms has one lead wire connected as at 25 and its opposite lead wire connected as at 30 to the wire 20. The lead wire 18 of the lamp C is connected at 22 to the wire 23.

and has arranged therein a resistor 31 of the value of 50,000 ohms. The other lead wire 17 of the lamp C is connected as at 32 to the wire 26 between the resistors 27 and 28.

These miniature neon glow lamps have a striking or breakdown potential of between 50 and 90 volts and in selecting lamps for these positions in the network, it is necessary to separate lamp having the lowest breakdown potential for the lamp A. After the lamps have been selected they are cured by placing them on a line of 110 volts for about twenty-four hours whereby they will maintain these selected starting potentials. In other words lamps A are selected as having a breakdown potential of between 50 and 60 volts, lamps B of between 60 and 70 volts and lamps C of about 90 volts. The carbon resistors should have a plus or minus tolerance of not more than 10% of their rated ohmage. The three resistors 21, 24 and 31 are current limiting resistors, one for each lamp A, B and C respectively whereas, the resistors 27, 28 and 29 are in a voltage divider arrangement so that the lamp C will strike on circuits of 440 volts or above only, lamp B will strike on circuits of 220 volts or above and lamp A will strike on circuits of 110 volts or above. Should these lamps be connected to circuits of 110 to 125 volts, only the lamp A will glow, when applied to circuits of 220 to 240, lamps A and B will glow and when applied to circuits of 440 to 600 volts all three lamps A, B and C will glow.

After fabricating the network of lamps, resistors and wires as shown in Fig. 9 of the drawings the same are pressed within recesses formed in the outer periphery of the core 5. The recess 32 33 and 34 of this core receive the lamps A, B, and C respectively. The resistor 21 and 31 are seated within the recesses 35 and 36 respectively and the resistors 24, 29, 27 and 28 are seated in the recesses 37, 38, 39 and 40 respectively. The wires 17 and 18 are seated within the groove 41 of the core. The wire 18 of the lamp B is seated within the groove 42 and its wire 17 extends through the groove 43. The wire 18 of the lamp C is seated within the groove 44 and its wire 17 passes through the groove 45. The transverse section of the wire 26 is seated within the groove 46 of the core. After the lamps, resistors and wires therefore are pressed within and seated in their respective grooves or recesses, the outer end of the wire 23 is inserted through a laterally extending opening 47 of the core 5 wherein it will have electrical contact with the holder 7. The outer end of the wire 20 extends through the slot 48 and is electrically connected to the knotted end of the conductor 11. The core or plug 5 is then inserted through the opened lower end of the casing 1 and forced therein until the electrodes 16 of the lamp A register with the openings having the markings 110-125 adjacent thereto. The electrode of the lamp B will then register with the openings having the markings 220-240 adjacent thereto and the electrodes of the lamp C will register with the openings having the markings 440-600 adjacent thereto.

In use and operation of this instrument, one may hold the casing in one hand and apply the contact pin 8 to one conductor of an electrical circuit, the voltage of which is to be visibly indicated. The handle 12 is grasped in the other hand and its contact pin 8 applied to the other conductor of the electrical circuit. Should only one electrode of each lamp appear to glow through the openings 2 of the casing, it will

indicate that the electrical circuit is of direct current and if both electrodes glow it will indicate that the electrical circuit is of alternating current. If only lamp A glows it will indicate an electrical circuit of between 110 and 125 volts. Should lamps A and B glow, it will indicate an electrical circuit of between 220 and 240 volts and if all three lamps A B and C glow, it will indicate an electrical circuit of between 440 and 600 volts.

The tubes 1 and 12 of insulation material have relatively thick walls as a safety measure and the core 5 is removably inserted within the tube 1 so that access may be gained to the electrical connections therein should they become broken. The thick walls of the tube 1 help one to more readily see the lamps through the openings 2 and determine if one or both electrodes of the lamps appear to be glowing.

I claim:

1. A voltage indicator comprising in combination a tubular casing formed of one piece of insulating material and having its opposed ends opened, said casing having a row of light emitting openings formed therein, a cylindrical core formed of one piece of insulating material and insertable through either opened end of said casing, said core being of the same length as that of said casing and having recesses formed within the outer periphery thereof, lamp indicators seated within the recesses of said core, a series of resistors and wires electrically connected to said lamp indicators and seated within other recesses formed in said core, said core having an exterior diameter substantially the same as that of the interior diameter of said casing whereby said casing will contact and retain the said lamp indicators and said series of resistors and wires within the recesses of said core and permit the light rays from the lamp indicators to emit through the row of openings therein, contact terminals connected to the opposite ends of said core and electrically connected to the wires seated within the recesses of said core, and said contact terminals extending from the opened ends of said casing.

2. A voltage indicator comprising in combination a tubular casing having its opposite ends opened, a removable cylindrical core formed from one solid piece of insulating material of a length the same as that of said casing, the exterior diameter of said core being the same as that of the interior diameter of said casing whereby said core may be inserted within the casing through one of the opened ends thereof, lamp indicators seated within said core whereby light rays therefrom may emit through openings formed within said casing, said core having a longitudinally extending recess formed therein, an adjustable contact terminal seated within said recess and extending from one end of said casing, said core having a slot formed within the opposite end thereof, a flexible conductor having one end secured within the slot of said core and extending from the opposite end of said casing, means for electrically connecting said lamp indicators to said adjustable contact terminal and said flexible conductor, and a contact terminal connected to the opposite end of said flexible conductor.

3. A voltage indicator comprising in combination a holder, said holder being formed from a single unitary piece of cylindrical insulating material having its opposed ends opened, a removable tray insertable through the opposed opened

ends of said holder, said tray being formed from a single piece of cylindrical insulating material and of substantially the same length as that of said holder for closing the opposed ends thereof when insertable therein, a visible indicating network seated within said tray, said visible indicating network contacting said holder whereby the latter will retain the same within said tray and said holder having openings therein whereby said indicating means may be visible exteriorly there- 10 of.
